UNITED STATES PATENT OFFICE.

EDGAR EARLE LITTLEFIELD, OF LOS ANGELES, CALIFORNIA.

VALVE.

Application filed March 18, 1922. Serial No. 544,878.

My invention relates to electrically actuated valves and consists of improvements which provide a valve capable of operation on low current consumption and comparatively low voltage. It also provides a valve capable of operation on either alternating or direct current.

By employing a by-pass principle of construction in conjunction with electrically actuated means I have provided a combination which is highly efficient and economical in power consumption. The means employed are as will appear.

In the drawings Figure 1 is a partial vertical section and a partial front elevation of my invention. Figure 2 is a plan view on line X²—X².

My valve mechanism comprises a casing 1 having an entrance opening 21 and an outlet opening 28 ordinarily screw-threaded as shown in Fig. 1 adapting the valve casing to be coupled to fluid pipes in the usual manner. Within the casing 1 I provide a partition 30 having preferably a raised flat top 25 constituting a valve seat 25. A valve 9, preferably having a flat bottom is adapted to seat on the valve seat 25. The valve preferably has packing 33 and a screw 33' to hold the packing in its place. The screw 33' has a hole 8' therethrough as shown in dotted lines, Fig. 1.

At the top of the valve casing I preferably insert a bonnet 12, there being a screw-thread connection between the bonnet 12 and the casing 1. The bonnet 12 conveniently comprises a downwardly extending portion 13 and a shoulder 32. Above the shoulder I conveniently provide a water chamber 18 in the upper portion of the bonnet 12. The valve 9 extends upwardly from the valve seat 25 and is provided with a piston portion 9' preferably fitting loosely in the downward extension 13 of the bonnet 12. Of course the piston portion 9' must be sufficiently larger relatively to seat 25 than the valve 9 so that the pressure of the water in the casing 1 will raise the valve off its seat 25 when pressure is removed from the top of the piston portion 9'.

To remove the pressure from the top of the piston portion 9' I provide a by-pass 8 as shown in Fig. 1 which extends entirely through the valve and as shown in the drawings communicates at one end with the hole 8' in the screw 8 and thence with the outlet 28 of the casing 1 and at the other end the

by-pass communicates with the water chamber 18. The top of the water chamber 18 as shown in Fig. 1 is closed by a hollow core 35 flanged at its bottom as shown and a nut 36 screw-threaded to the upper portion of the bonnet 12 clamps the flange of the hollow core 35 to the top of the bonnet 12. The hollow core constitutes the core of a solenoid 15 which is closed by a stationary iron plug 4, the solenoid having the usual terminals 16 and 17 whereby connection may be made with a source of current.

Within the hollow core 35 I preferably provide a magnetizable sleeve 6 loosely fitting around a small valve stem 5 preferably of non-magnetic metal. This valve stem terminates at its lower end preferably in a cone-shaped needle valve which is adapted to cooperate with the upper end of the by-pass 8 and serve to open and close the by-pass 8 as will hereinafter be pointed out.

The upwardly extended piston 9' of the valve 9 may fit sufficiently loosely in the downwardly extending portion 13 of the bonnet 12 and it forms a valve for cooperation with the shoulder 32 of the bonnet which serves as a valve seat and this valve and seat separates the water in the water chamber 18 when it is closed from the water below except through the by-pass 8 when the by-pass 8 is open. I may, however, instead of depending altogether on the loose fit of the piston 9' in the extension 13, provide a passage 31 through the piston portion 9' as shown in Fig. 1. A shoulder 38 on the lower end of the valve stem 5 prevents the sleeve 6 from passing down over the needle valve at the lower end of the valve stem 5.

The operation of the device is apparent from the foregoing description and briefly stated is as follows:—Assuming that the valve 9 is seated on the valve seat 25 and the valve stem 5 with the valve at its lower end is seated on the valve seat 24 around the upper end of the by-pass 8 and the circuit through the terminals 16 and 17 is closed, the sleeve 6 will be drawn into the hollow core 35 and strike the upper end of the valve stem 5 and will lift the valve from its seat 24 thus allowing the water in the chamber 18 to escape through the by-pass 8. Of course the capacity for water flow through the by-pass 8 is somewhat greater than around the piston 9' or by-pass 31 which allows the water in the chamber 18 to es-

cape therefrom through the by-pass 8 and thus remove the pressure on the top of the valve 9 and the piston portion 9' being somewhat larger than the valve seat 25, the 5 water pressure in the valve casing will lift the valve 9 from its seat and will allow the water to pass through the inlet 21 and out of the outlet 23 of the valve casing. This flow will continue until the circuit through 10 the terminals 16 and 17 is broken when the sleeve 6 and the valve stem 5 will drop and close the by-pass 8, the water continuing to flow into the water chamber 18 around the piston portion 9' of the valve or through 15 the by-pass 31 until the pressure in the chamber 18 will force the valve 9 to its seat 25 and thus stop the flow through the openings 21 and 28.

Since the magnetizable sleeve 6 has lost 20 motion between the upper end of the valve stem 5 and the shoulder 38 it will have a hammer action on the valve stem to raise it and lower it as described.

It will thus be noticed that the only electric 25 current required to operate the valve 9 is the small amount necessary to raise the small valve stem 5 by operating the magnetizable sleeve 6.

For energizing the coil of the solenoid I 30 have found that the energy supplied by the secondary circuit of a small transformer supplying 75 watts at from 18 to 28 volts is sufficient. However, current from any suitable source may be employed as desired.

This valve constitutes an improvement on the prior art as represented by the valve of the patent to Schmidt, Number 959,618, patented May 31, 1910. The by-pass principle may be found employed in many types of 40 valves. Certain features of the present one may be found in one type manufactured by the Foster Engineering Company, Newark, New Jersey. My invention supplies a combination of many valuable features which 45 make of it a superior device in many respects.

I claim—

1. A valve mechanism comprising a casing having main inlet and outlet openings, 50 a main valve seat a second valve seat and a water chamber in the casing, a main valve cooperative with said main valve and second valve seats and having by-passes communicating respectively with the casing inlet and outlet, one of the bypasses being a narrow passage through the valve and having a valve seat at one extremity of the passage, a small valve stem having a valve at one end cooperating with the by-pass valve seat, and 55 electrical means for operating said valve stem.

2. A valve mechanism comprising a casing having main inlet and outlet openings, a flat face main valve seat and a second valve 60 seat in the casing and a water chamber in

the upper portion of the casing, a main valve cooperative with both said seats and having by-passes communicating respectively with the casing inlet and outlet, one of the bypasses being a narrow passage through the valve with a valve seat surrounding its upper end, a valve stem tapered to form a valve cooperative with the by-pass valve seat and electrical means for operating said valve stem. 75

3. A valve mechanism comprising a casing having main inlet and outlet openings, a main valve seat and a water chamber in said casing, a main valve for said seat with bypasses communicating respectively with the casing inlet and outlet, one of the bypasses being a small passage through the main valve and having a valve seat at its upper extremity, an electromagnet having a tubular core, a valve stem extending into said core and formed at its lower end into a valve cooperative with the by-pass valve seat in the main valve. 80

4. A valve mechanism comprising a casing having main inlet and outlet openings, a main valve seat and a water chamber in the casing, a main valve for said seat, said casing having a tubular portion above the main valve, said valve having a piston portion in said tubular portion, a valve seat in the tubular portion, the upper end of the piston portion of the main valve forming a valve cooperative with said last mentioned valve seat, bypasses communicating respectively with the casing inlet and outlet, one of the bypasses being a small passage having a valve seat at its upper extremity, a valve stem shaped to form a valve at its lower end cooperative with the by-pass valve seat, and electrical means for operating said valve stem. 90

5. A valve mechanism comprising a casing having main inlet and outlet openings, a main valve seat in said casing and a main valve cooperative therewith, a bonnet with a downwardly extending tubular portion in the upper portion of the casing, and also having a valve seat therein, said main valve having a piston portion operable in said downwardly extending tubular portion of the bonnet, the upper portion of the piston portion forming a valve cooperative with the valve seat in the bonnet, there being a by-pass in the piston portion of the main valve terminating at its upper portion in a valve seat, a valve stem with its lower end forming a valve cooperative with said last mentioned valve seat, and electrical means for operating the valve stem. 100

6. A valve mechanism comprising a casing having main inlet and outlet openings and a water chamber therein, a seat within said casing arranged to support the weight of a main valve, a main valve supported by said seat, bypasses communicating respectively 110

with the casing inlet and outlet, one of the by-passes being a passage through the main valve and having a valve seat at one extremity of the passage, a second valve member having a valve at one end co-operating with the by-pass valve seat, said member displacing less fluid than the main valve, and electrical means forming a part of the water chamber for operating said second valve member.

7. A valve mechanism comprising a casing having main inlet and outlet openings and having an imperforate part of its wall forming a chamber, an armature within the chamber an auxiliary valve controlled by the armature, a main valve provided with a by-pass having a seat, the auxiliary valve co-operating with said seat, the weight of the auxiliary valve being less than that of the main valve, and electrical means controlling said armature.

8. A valve mechanism comprising a casing having main inlet and outlet openings and having an imperforate part of its wall forming a chamber, a seat within said casing arranged to support the weight of a main valve, a main valve supported by and having cushioned engagement with said seat, said valve having a by-pass with a valve seat at one extremity thereof, an auxiliary valve device co-acting with the seat of said by-pass, said auxiliary valve device having an armature within said chamber, and electrical means controlling said armature.

9. A valve mechanism comprising a casing having main inlet and outlet openings, a seat arranged to support the weight of a main valve within said casing, a main valve co-operating with said seat, said valve having a by-pass with a valve seat at one end of the main valve, a small auxiliary valve device co-operating with said by-pass seat, and electrical means including a sleeve within the casing for controlling the auxiliary valve device.

10. A valve mechanism including a casing having main inlet and outlet openings, said

casing also having therein a chamber for a main valve and a smaller chamber for an auxiliary valve member, a seat in the main valve chamber arranged to support the weight of a main valve therein, a main valve co-operating with said seat, said valve having a by-pass provided with a seat on the valve, an auxiliary valve member within said smaller chamber, said auxiliary valve member having a valve cooperative with the seat of the by-pass on the valve, and electrical means controlling the auxiliary valve member.

11. A valve structure comprising a main valve, a valve seat, a chamber open to line pressure when the main valve is closed, a second valve seat in said chamber, said main valve being cooperative with both valve seats, means for releasing the pressure in the chamber and unseating the main valve from the second valve seat, said means including a second small valve, the latter having a seat on the main valve.

12. A valve structure comprising a main valve, an orifice terminating in a valve seat in the upper portion of the main valve, a pressure chamber above the main valve and a small needle-like valve entirely enclosed in the pressure chamber cooperative with the seat on the upper end of the main valve, and electrical means to operate the small valve.

13. A valve structure comprising a main valve, a casing with a pressure chamber therein above the main valve, an orifice in the main valve and a valve seat surrounding the orifice, a small valve having a small long stem extending through said chamber, a magnetizable sleeve on the small stem also enclosed in said chamber and guided in its movements by the sides of the chamber and electrical means for operating the sleeve.

In testimony whereof I have hereunto affixed my signature at Los Angeles, California, this 13th day of March, 1922.

EDGAR EARLE LITTLEFIELD.
